US00D669172S

(12) **United States Design Patent**
McGrail et al.

(10) **Patent No.:** US D669,172 S
(45) **Date of Patent:** ** Oct. 16, 2012

(54) **VISUALIZATION INSTRUMENT**

(75) Inventors: **Thomas W. McGrail**, Cicero, IN (US); **David J. Miller**, Pittsburg, KS (US); **Yung Siung Tony Yeh**, Libertyville, IL (US); **Kristin Jugenheimer Size**, Waltham, MA (US); **Randal Chinnock**, Eastford, CT (US); **George Grubner**, Needham, MA (US); **Elizabeth Powell Goodrich**, Roslindale, MA (US); **Paul Gregory**, Watertown, MA (US); **Gary Palladino**, Cambridge, MA (US); **Brian Hack**, Cambridge, MA (US)

(73) Assignee: **King Systems Corporation**, Noblesville, IN (US)

(**) Term: **14 Years**

(21) Appl. No.: **29/422,941**

(22) Filed: **May 25, 2012**

(57) **CLAIM**

The ornamental design for the visualization instrument, as shown and described.

DESCRIPTION

FIG. 1 is a front elevation view of a visualization instrument of the present design;

FIG. 2 is a front perspective view of the visualization instrument shown in FIG. 1;

FIG. 3 is a right elevation view of the visualization instrument shown in FIG. 1;

FIG. 4 is a left elevation view of the visualization instrument shown in FIG. 1;

FIG. 5 is a rear perspective view of the visualization instrument shown in FIG. 1;

FIG. 6 is a rear elevation view of the visualization instrument shown in FIG. 1;

FIG. 7 is a top plan view of the visualization instrument shown in FIG. 1; and,

FIG. 8 is a bottom plan view of the visualization instrument shown in FIG. 1.

The broken lines encompassing unshaded regions represent the bounds of the claimed design while all other broken lines are directed to environment and are for illustrative purposes only; the broken lines form no part of the claimed design.

1 Claim, 7 Drawing Sheets
